(57) CLAIM

The ornamental design for a washing machine as shown and described.

DESCRIPTION

FIG. 1 is a perspective view of a washing machine showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof showing the state that during operation, the front part of this washing machine has been become transparent; and,

FIG. 9 is a perspective view showing the state that the detergent box at the upper part of the washing machine has been opened.

The broken line showing of details in FIGS. 4, 6, 7, 8 and 9 is included for the purpose of showing portions of the washing machine that form no part of the claimed design.

1 Claim, 9 Drawing Sheets

FIG. 1

FIG. 2

FIG. 3

FIG. 4

FIG. 5

FIG. 6

FIG. 7

FIG. 8

FIG. 9
